UNITED STATES PATENT OFFICE.

MAX BRETSCHNEIDER, OF PLAUEN, GERMANY.

EMBROIDERY NEEDLE FOR USE IN CONNECTION WITH MULTINEEDLE EMBROIDERY MACHINES.

Application filed June 15, 1922. Serial No. 563,542.

To all whom it may concern:

Be it known that I, MAX BRETSCHNEIDER, a citizen of the German Republic, and a resident of Plauen, Saxony, Germany, have invented a new and useful Improved Embroidery Needle for Use in Connection with Multineedle Embroidery Machines (for which I have filed application in Germany March 6, 1920), of which the following is 10 a specification.

This invention relates to longitudinally slotted embroidery needles intended for the working of a beaded embroidery thread on a multi-needle embroidery machine. Working 15 such a thread on such a machine by such a needle is at present effected in such a manner that on the return motion of the needle a dead loop of the embroidery thread is drawn into the rear end of the slot, after 20 which the front portion of that loop is automatically removed from the eye, whereas the rear portion of the same is threaded into it. The manner in which the slot terminates 25 into the eye of the needle is of pre-eminent importance for the proper functioning of the machine. First of all, care must be taken that the thread does not leave the eye at the commencement of the forward motion of the needle or at the formation of 30 the loop, and does not glide back in the slot, because this gives rise to faulty stitches. That occurs if, the slot is made to terminate 35 into the eye at the front end of this latter without any provisions against the thread getting back into the slot. To obviate such an occurrence the thin intermediate tongue provided between the slot and the rear end 40 of the eye has been made elastic and bent against the opposite wall of the slot, but then the thread when entering into the eye 45 is bound to bend back that tongue a little which diminishes its durability by reason of the friction produced and is also adverse to the employment of fine embroidery threads. It is to be borne in mind that at 50 each stitch two portions of the thread must pass through the narrowed mouth of the slot at the eye. It is, therefore, unavoidable that if several stitches closely follow each 55 other the thread portions concerned are weakened in the narrow mouth of the slot and the thread is exposed to the danger of breaking which takes place especially if the tongue has become worn off and its edges sharpened which act like a knife

blade. This evil is still increased if the intermediate tongue is allowed to extend into a trough-shaped cavity of the opposite wall of the slot.

Now, in order to do away with the various 60 drawbacks experienced with the above-mentioned known embroidery needles, especially to make the thread enter into the eye with the least friction possible but preventing it from getting back into the slot, I make the 65 slot terminate into the eye in open state and in oblique position, as fully described hereinafter and shown in the accompanying drawing in which one form of construction is illustrated by way of example. In the 70 drawing Fig. 1 shows that side of the needle which is directed towards the shuttle path. Fig. 2 shows that side of the needle along which the shuttle passes. Fig. 3 is a longitudinal section on line A—A of 75 Fig. 1. Fig. 4 is a longitudinal section on line B—B of Fig. 1. Fig. 5 is a transverse section on line C—C of Fig. 1. Fig. 6 is a transverse section on line D—D of Fig. 1. Fig. 7 is a transverse section on 80 line E—E of Fig. 1. Fig. 8 is a transverse section on line F—F of Fig. 1. And Fig. 9 is a somewhat diagrammatic representation (drawn on a smaller scale) which shows the position of the oblique slot-end 85 with respect to the shuttle race.

Concerning the main parts or portions of the needle, there are to be distinguished the shaft 1, the point 2, the tongue 3, and the rear end 4 which, preferably, is bent 90 at its place of junction with the shaft and serves for attaching this latter to the so-called needle-bar. The tongue 3 is separated from the shaft 1 by a longitudinal slot 5, the front end of which terminates 95 laterally into the eye 6 by means of a transverse slot 7. Owing to this arrangement and configuration of the portions concerned a small tongue 8 is formed between the eye 6 and the slot 5. Now, conformably with 100 the present invention, the transverse slot 7 is to lie obliquely with respect to the axis of the eye 6 (Figs. 1 and 4) so that it terminates into the eye on one side of the needle at the front end of the eye, and on the other side of the needle at the rear end of the eye, in consequence of which the configuration of the tongue 8 is somewhat like a triangle. A portion of the tongue 3 viz., near the point 2, is thickened towards the 110

eye 6 (Fig. 6) and forms a portion of the wall of the same, viz., of that wall, of which also the tongue 8 forms a portion. Owing to this configuration of the slot 5 between the tongues 3 and 8 a thread threaded into the eye cannot possibly leave this latter, that is to say, get back into the slot 5 if it is held fast on that side of the needle where the slot 5 terminates at the front end of the eye, and is moved in a circular path round the axis of the eye at the opposite side of the needle. This circumstance renders possible a reliable work with the novel needle, it being presupposed that it is properly clamped to the needle bar of the embroidery machine. This is the case if that side of the needle at which the slot 5 terminates into the front end of the eye is directed towards the shuttle race, as shown in Fig. 9, because on this side the thread 10 during the formation of the loop, is prevented by the usual needle channel from making any motions of its own, that is to say, motions by which the thread could get from the eye 6 into the slot 5 at the front end of the tongue 8. On the other hand, the spontaneous thread motions taking place, during the loop formation, on the other side of the needle are completely harmless. For the working procedure which results with embroidery machines having a suspended shuttle, such as 11, Fig. 9, that needle side where the slot 5 terminates at the front end of the eye must be directed upwards. The main portion of the needle has, preferably an approximately square-shaped transverse section, as shown in Figs. 6-8, but the point must have a circular section, as in Fig. 5. The shaft has a long longitudinal groove 13 which lies in the plane of the eye 6 and communicates with this latter, and the object of which is to protect the thread whilst passing through the fabric. The rear portion of the shaft 1 is reduced

in thickness at the side of the slot 5, and forms there an oblique surface 1' which serves as a guide-surface for the thread and diminishes the friction to which the thread is subjected.

There has been described in the foregoing lines a needle the longitudinal slot of which terminates laterally into the eye, but this is not absolutely essential for carrying the invention into effect. I wish it to be understood that I do not limit myself to such forms of construction, as other constructions of the invention are possible, the only condition being that the mouth of the slot at the eye lies or stands obliquely with respect to the axis of the eye so that spontaneous unthreading of the needle is impossible.

Having now described my invention, what I claim as new and desire to secure by Letters Patent of the United States is:

1. A needle for working a beaded thread on a multi-needle embroidery machine, having a longitudinal slot terminating in a transverse slot arranged obliquely relative to the axis of the needle and of which one end terminates in the front and the other in the rear end of the eye of the needle.

2. A needle for working a beaded thread on a multi-needle embroidery machine, having a longitudinal slot the front end of which terminates laterally in a transverse slot arranged obliquely relative to the axis of the needle and terminating at one side of the needle in the front end of the eye and the opposite side of the needle in the rear end of the eye, said transverse slot producing an angular tongue.

In testimony whereof I affix my signature in presence of two witnesses.

MAX BRETSCHNEIDER.
